United States Patent Office.

BENJAMIN G. FULLER, OF BALTIMORE, MARYLAND.

Letters Patent No. 77,027, dated April 21, 1868.

IMPROVEMENT IN HYDRANTS.

The Schedule referred to in these Letters Patent and making part of the same.

TO WHOM IT MAY CONCERN:

Be it known that I, BENJAMIN G. FULLER, of Baltimore, in the county of Baltimore, and State of Maryland, have invented certain new and useful Improvements in Hydrants; and I hereby declare the following to be a full, clear, and exact description of the same, reference being had to the accompanying drawings.

One of the causes which most frequently induces the bursting of water-pipes used in connection with hydrants, arises from the sudden checking of the stream of water flowing through the pipes and out of the hydrant. If, for instance, the hydrant-valve be suddenly closed, the stream of water will be suddenly checked by the closed valve, while its head or impetus remains for the moment unabated. As the water cannot move forward, its impetus will cause it to be forced against the sides of the pipe, and the pressure thus induced will burst the pipe if it be at all weak or imperfect.

To remedy this difficulty, the lower or induction-end of the hydrant has been surrounded by a cylinder or chamber, the air within which constitutes an elastic and compressible cushion, upon which the impetus or head of water is expended when the hydrant-valve is closed, so as to effect the gradual checking of the stream without undue pressure upon the pipe.

Within this chamber the valve and valve-mechanism for regulating the flow of water are held, but their arrangement heretofore has been such, that, in event of the disarrangement or breaking of any of the parts, it has been impossible to get at them with facility, in order to repair or remove them, without first digging up the air-cylinder or box by which they are surrounded, and this operation, owing to the depth at which the cylinder is placed in the earth, is necessarily troublesome and laborious. My invention is intended to obviate this evil, and to this end it consists in the special arrangement and construction of the valve; valve-mechanism, and surrounding air-cylinder, in the manner hereinafter described, so that the said valve and mechanism may be easily and readily removed, when desired, from the cylinder, without moving or disturbing the latter.

To enable those skilled in the art to understand and use my invention, I will now proceed to describe the manner in which the same is or may be carried into effect, by reference to the accompanying drawings, in which—

Figure 1 is a vertical central section through the lower or induction-end of a hydrant, constructed in accordance with my invention.

Figures 2, 3, and 4, are plan views of detached parts of the same.

Figure 5 is a vertical central section through the upper part of the hydrant, which, being of ordinary construction, need not be particularly referred to.

The lower part of the hydrant, as shown in fig. 1, consists of the air-cylinder A, connected by a screw-joint with the upper or piston-cylinder e, communication between the two chambers taking place through the tube 1. This tube is screwed into the neck of the upper cylinder e, and extends down to near the bottom of the chamber A. The upper end of the tube which lies within the cylinder e, is shaped so as to have the form of a six-sided nut, as shown plainly in fig. 2 of the drawings. The tube is closed at its lower end by a valve, a, which bears against a seat, b, on the under side of the end of the same. A valve-stem, c, surrounded by a spiral spring, d, extends up through the tube 1, and its upper end is attached to a perforated cap, 3, which is of the diameter of the neck of the tube. This cap is pressed upon by but not attached to a larger piston or valve, which fits tightly in the upper chamber or cylinder e of the hydrant, and is united with the rod 3", which is operated by the crank B in the upper part of the hydrant. The cylinder e is screwed upon the upper end of the tube 1, as shown in fig. 1, so as to form a perfectly tight joint, and is provided with the eduction-pipe f, which communicates with the hydrant-spout C, fig. 5. Upon the lower end of the tube 1 is screwed a perforated cap or strainer, 2, which surrounds the valve a.

When the valve a is depressed by means of the rod 3" and handle B, so as to open the lower end of the tube 1, the water entering the perforated cap 2, through the orifice l in the cylinder A, will flow upward through the tube, and out from the upper perforated cap 3, which in this case will be depressed, so as to fit in and close the neck of the tube 1. As the cylinder or chamber e is tightly closed by the piston, the water will pass up through the pipe f, and out through the nozzle or spout C.

When it is desired to shut off the water, the hand of the operator is removed from the crank B, whereupon the spring d instantly draws up the valve a against its seat, and prevents the further flow of the water. As soon as this takes place, the impetus of the water will be expended upon the air cushion in the upper part of cylinder A, which cushion will be gradually compressed until it is of sufficient density to check the forward tendency or movement of the water, and the latter will thus gradually and slowly lose its impetus without causing any appreciable strain to be brought upon the induction-pipe.

That portion of the hydrant shown in fig. 1, is set in the ground just below the point where the earth ceases to be frozen. When the stream of water is shut off, therefore, such water as remains in the induction-pipe f falls back into the open tube 1, and the lower part of the cylinder or chamber e, and is thus prevented from being frozen in the upper and exposed portion of the pipe f.

If at any time the valve and valve-mechanism should get out of order, the construction and arrangement of the parts admit of their being readily detached and lifted out from the hydrant. The pin by which the piston-rod 3" is connected with the crank B is first removed, and the piston-rod and its piston, (which, as before mentioned, is unattached to the valve-rod e,) are drawn out from the hydrant. This operation uncovers the top of the tube 1, and by using a wrench of suitable shape to fit the nut upon the upper end of said tube, the tube may be unscrewed and detached from the cylinder e, and withdrawn, together with the valve and valve-appurtenances from the chamber A. This latter operation may be effected by means of a hook, which should be caught under the flange of the cap 3. I am thus enabled, without trouble or delay, to remove and replace that portion of the mechanism of a hydrant which is ordinarily most difficult of access, at the same time that it is most liable to become damaged or to get out of order.

Having now described my invention, and the manner in which the same is or may be carried into effect, what I claim, and desire to secure by Letters Patent, is—

The combination, with the air-chamber and the piston-cylinder of the hydrant, of the valve and herein-described valve-mechanism, operated by but not attached to the piston-head, and held within a tube or case, constructed and connected with the said air and piston-cylinders or chambers, in the manner and for the purposes shown and specified.

In testimony whereof, I have signed my name to this specification before two subscribing witnesses.

B. G. FULLER.
